ABSTRACT

A toothbrush includes a handle, and a head at an end of the handle having a thickness, a first surface, and an opposed second surface. Tooth cleaning elements extend outwardly from the first surface and have a length. A tissue cleanser is positioned on the second surface and has a plurality of tissue engaging elements and a height. A head height includes the thickness of the head, the length of the tooth cleaning elements, and the height of the tissue cleanser, and is less than 17.7 mm.

TOOTHBRUSH WITH LOW PROFILE HEAD

FIELD OF THE INVENTION

This invention relates generally to toothbrushes, and, in particular, to a toothbrush having tooth cleaning elements and a tissue cleanser with a low profile head.

BACKGROUND OF THE INVENTION

According to the American Dental Association, a major source of bad breath in healthy people is microbial deposits on the tongue, where a bacterial coating harbors organisms and debris that contribute to bad breath. One particular spot on the tongue that harbors significant quantities of odor-causing bacteria is the back of the tongue. The tongue is a haven for the growth of microorganisms since the papillary nature of the tongue surface creates a unique ecological site that provides an extremely large surface area, favoring the accumulation of oral bacteria. Anaerobic flora and bacteria residing on the tongue play an important role in the development of chronic bad breath commonly called halitosis. In general, the bacteria produce volatile sulfur compounds (VSC). If there is enough buildup of the sulfur compounds, the result can be lead bad breath or oral malodor. There is also evidence supporting the breath freshening benefits of cleansing cheek surfaces to remove dead skin cells, which ultimately will settle on the tongue surface becoming a source of protein for a host of odor causing bacteria.

Consequently, tissue cleansers have been added to a face of the head of a conventional toothbrush opposite the face on which the tooth cleaning elements are positioned. Adding a tissue cleanser increases the head height of the brush. Using a conventional toothbrush having tooth cleaning elements and a tissue cleanser to clean the back of the tongue often results in the gag reflex due to inadvertent contact with the back of the throat, due to the increased head height of the brush. This increase in head height also negatively affects the tooth cleaning efficacy of the brush, making brush head access to hard to reach areas, such as the buccal surfaces of the third molars, difficult due to restricted access between cheeks and teeth. Previous efforts seen in the art to improve oral access have typically focused on the "head size", as evidenced by the offering of "compact", and even "ultra-compact" head sizes. These smaller head sizes have in fact only focused on reducing the length and width of the brush head, and have ignored the overall brush head height, the primary restriction in accessing tight buccal spaces, and primary cause of the gag reflex when cleansing the back of the tongue.

It would be desirable to provide a toothbrush with tooth cleaning elements and a tissue cleanser that reduces or overcomes some or all of the difficulties inherent in prior known devices. Particular objects and advantages will be apparent to those skilled in the art, that is, those who are knowledgeable or experienced in this field of technology, in view of the following disclosure of the invention and detailed description of certain embodiments.

SUMMARY

The principles of the invention may be used to advantage to provide a toothbrush with tooth cleaning elements and a tissue cleanser with a reduced profile. In accordance with a first aspect, a toothbrush includes a handle, and a head at an end of the handle having a thickness, a first surface, and an opposed second surface. Tooth cleaning elements extend outwardly from the first surface and have a length. A tissue

2

cleanser is positioned on the second surface and has a height. A head height includes the thickness of the head, the length of the tooth cleaning elements, and the height of the tissue cleanser, and is less than 17.7 mm.

- 5 In accordance with another aspect, a toothbrush includes a handle and a head at an end of the handle having a thickness of approximately 3.6 mm, a first surface, and an opposed second surface. Tooth cleaning elements extend outwardly from the first surface and have a diameter of less than 7 mil (0.007"). A tissue cleanser on the second surface has a plurality of nubs and a height of approximately 0.5 mm. A head height includes the thickness of the head, the length of the tooth cleaning elements, and the height of the tissue cleanser, and is less than 17.7 mm.
- 10 Substantial advantage is achieved by providing a toothbrush with tooth cleaning elements and a tissue cleanser with a reduced profile. In particular, certain embodiments of a toothbrush with tooth cleaning elements and a tissue cleanser with a reduced profile allow a user to more comfortably clean tissue deep in the mouth, helping to reduce the body's natural gag reflex. A further advantage is gained in tooth cleansing by providing improved access to tight buccal surfaces. A further advantage is offered in cleaning cheek surfaces opposite third molars, as the soft tissue cleanser is able to reach further into the tight pocket space between third molars and cheeks.
- 15

These and additional features and advantages disclosed here will be further understood from the following detailed disclosure of certain embodiments.

BRIEF DESCRIPTION OF THE DRAWINGS

FIG. 1 is a perspective view of a toothbrush with tooth cleaning elements and tissue engaging elements.

FIG. 2 is an end elevation view of the head of a prior art toothbrush.

FIG. 3 is an end elevation view of the toothbrush of FIG. 1.

FIG. 4 is an end elevation view of an alternative embodiment of a toothbrush with tooth cleaning elements and tissue engaging elements.

FIG. 5 is an end elevation view of another alternative embodiment of a toothbrush with tooth cleaning elements and tissue engaging elements.

FIG. 6 is an end elevation view of a further alternative embodiment of a toothbrush with tooth cleaning elements and tissue engaging elements.

The figures referred to above are not drawn necessarily to scale and should be understood to provide a representation of the invention, illustrative of the principles involved. Some features of the toothbrush depicted in the drawings have been enlarged or distorted relative to others to facilitate explanation and understanding. The same reference numbers are used in the drawings for similar or identical components and features shown in various alternative embodiments. Toothbrushes as disclosed herein would have configurations and components determined, in part, by the intended application and environment in which they are used.

DETAILED DESCRIPTION OF CERTAIN PREFERRED EMBODIMENTS

- 60 FIG. 1 illustrates an oral care implement, such as a toothbrush 10, having a handle 12 and a head 14, which may be used for cleaning the teeth and soft tissue in the mouth, such as the tongue, interior surfaces of the cheeks, lips or the gums.
- 65 Handle 12 is provided for the user to readily grip and manipulate the toothbrush, and may be formed of many different shapes and constructions. Head 14 has a first face 16 that

supports tooth cleaning elements **18** and an opposed second face **20** that supports a tissue cleanser **22**.

As use herein, the term "tooth cleaning elements" includes any type of structure that is commonly used or is suitable for use in providing oral health benefits (e.g., tooth cleaning, tooth polishing, tooth whitening, massaging, stimulating, etc.) by making intimate contact with portions of the teeth and gums. Such tooth cleaning elements include, but are not limited to, tufts of bristles **21** that can be formed to have a number of different shapes and sizes, and elastomeric cleaning members **23** that can be formed to have a number of different shapes and sizes, or a combination of both tufts of bristles and elastomeric cleaning members. Bristle tufts may be arranged on first face **16** in any configuration.

The bristle tufts may be formed with bristles of the same or different bristle materials (such as nylon bristles, spiral bristles, rubber bristles, etc.). Moreover, while tooth cleaning elements **18** may be arranged so that they are generally perpendicular to first face **16**, some or all of tooth cleaning elements **18** may be angled at various angles with respect to first face **16**. When first face **16** includes bristle tufts, it is thereby possible to select the combination of bristles configurations, bristle materials and bristle orientations to achieve specific intended results and operational characteristics, thus maximizing and enhancing cleaning, tooth polishing, tooth whitening, massaging, and stimulation.

The bristle tufts may be arranged by any conventional method. For example, the bristle tufts may be stapled to head **14**. In certain embodiments, tooth cleaning elements **18** in the form of strands or bristles can be attached via in-mold tufting (IMT) methods that generally require small cross-sections of material into which the strands are permanently attached. The strands utilizing IMT methods may be attached during formation of the handle **12** or during formation of head **14**, which is the portion of toothbrush **10** to which the strands and other materials are attached.

In other embodiments, tooth cleaning elements **18** in the form of strands or bristles may be attached via anchor free tufting (AFT). In the AFT brush making process, described in detail in U.S. Pat. No. 6,779,851, nylon is fed into a pre-molded plate that can be made from any thermoplastic or elastomer material or combination thereof. This nylon may be processed into bristle tufts of various sizes and shapes. The non-use or proximal end of the nylon is heated and melted to retain the nylon in the brush head when a reasonable pulling force is applied. This head plate may then be ultrasonically welded to a pre-molded handle that has a peripheral wall or frame on which the head plate will rest and become fused to the handle.

Tissue cleanser **22** may be formed of an elastomeric material, such as a biocompatible resilient material suitable for uses in an oral hygiene apparatus. To provide improved comfort as well as cleaning benefits, the elastomeric material preferably has a hardness property in the range of A8 to A25 Shore hardness. As an example, one embodiment of an elastomeric material is styrene-ethylene/butylene-styrene block copolymer (SEBS) manufactured by GLS Corporation. It is to be appreciated that SEBS material from other manufacturers, or other materials within and outside the noted hardness range could be used. Suitable materials for tissue cleanser **22** will become readily apparent to those skilled in the art, given the benefit of this disclosure.

A prior art toothbrush **26** is seen in FIG. 2. Tooth cleanser **22** of toothbrush **26** has a height A, measured from second surface **20**. Head **14** of toothbrush **26** has a thickness B, and tooth cleaning elements **18** of toothbrush **26** have a length C. Thus, it can be seen that the total head height H of toothbrush

14 is the combination of height A of tooth cleanser **22**, the thickness B of head **14**, and the length C of tooth cleaning elements **18**. Known prior art toothbrushes with tooth cleaning elements **18** and a tooth cleanser **22** have a head height H of approximately 19 mm.

In certain embodiments, as seen in FIG. 2, the profile or head height H of toothbrush **10** can be reduced by reducing length C of bristles **18**. Length C of bristles **18** is driven by a number of factors, including mouth feel, cleaning ability, 10 bristle durability, the type of material in which the bristles are secured, and manufacturing equipment limitations. As a general rule, the shorter the length of a toothbrush bristle, the thinner the fiber needed to maintain the appropriate brush 15 stiffness. The most common method to date of manufacturing toothbrushes has been with staple technology. With this process, there are practical limits on how small a diameter fiber one can use, with approximately 0.006 mil being the typical smallest fiber one can efficiently run. Nearer processes for 20 manufacturing toothbrushes offer the potential to reduce the limitations of conventional staple tufting. For example, IMT and AFT may be used, which allow bristles of a shorter length. AFT utilizes pre-end rounded bristles, which can allow end rounding of thinner bristles than conventional end rounding.

25 In certain embodiments, length C of bristles **18** can be produced, via IMT or AFT, for example, having a length significantly less than 13 mm.

In other embodiments, as seen in FIG. 4, the head height H of toothbrush **10** can be reduced by reducing the thickness B 30 of head **14**. Thickness B of head **14** is typically driven by the structure required to adequately hold bristles **18** in head **14**. In the case of staple technology, thickness B of head **14** typically runs between approximately 5.1 mm and approximately 6.2 mm. Using IMT and/or AFT brush making technologies, 35 which anchor bristles **18** in head **14** without metal staples, offer the ability to significantly reduce thickness B of head **14**. In certain embodiments, using IMT and/or AFT technologies, it has been found that adequate head strength can be maintained with thickness B of head **14** as small as approximately 40 3.6 mm.

45 Tissue cleanser **22** may include a plurality of tissue engaging elements **24**, which in certain embodiments are formed as nubs. As used herein a "nub" is generally meant to include a column-like protrusion (without limitation to the cross-sectional shape of the protrusion) that is upstanding from a base surface. In a general sense, the nub in such embodiments has a height that is greater than the width at the base of the nub. Nevertheless, nubs could include projections wherein the widths and heights are roughly the same or wherein the 50 heights are somewhat smaller than the base widths. Moreover, in some circumstances (e.g., where the nub tapers to a tip or includes a base portion that narrows to a smaller projection), the base width can be substantially larger than the height. Various embodiments of nubs **24** are described in 55 commonly owned U.S. Pat. No. 7,143,462, entitled "Oral Care Implement," the entire disclosure of which is hereby incorporated by reference in its entirety.

Such tissue engaging elements or nubs **24** are designed to 60 significantly reduce a major source of bad breath in people and improve hygiene. Nubs **24** enable removal of microflora and other debris from the tongue and other soft tissue surfaces within the mouth. The tongue, in particular, is prone to develop bacterial coatings that are known to harbor organisms and debris that can contribute to bad breath. This microflora 65 can be found in the recesses between the papillae on most of the tongue's upper surface as well as along other soft tissue surfaces in the mouth. When engaged or otherwise pulled

against a tongue surface, for example, nubs 24 provide for gentle engagement with the soft tissue while reaching downward into the recesses of adjacent papillae of the tongue. The elastomeric construction of nubs 24 also enables them to follow the natural contours of the oral tissue surfaces, such as the tongue, cheeks, lips, and gums of a user. Moreover, the soft nubs 24 are able to flex as needed to traverse and clean the soft tissue surfaces in the mouth along which they are moved.

In certain embodiments, as illustrated in FIG. 5, height A of tissue cleanser 22 can be reduced through the use of nubs 24. The thickness or width of the base of nubs 24 may range from about 0.51 mm to about 2.00 mm. Height A of nubs 24, as measured from second surface 20 to the tip of nubs 24 may be between approximately 0.5 mm and approximately 2.5 mm.

In light of the foregoing disclosure of the invention and description of various embodiments, those skilled in this area of technology will readily understand that various modifications and adaptations can be made without departing from the scope and spirit of the invention. All such modifications and adaptations are intended to be covered by the following claims.

The invention claimed is:

1. A toothbrush comprising:
a handle;
a head at an end of the handle and having a thickness, a first surface, an opposed second surface and a peripheral frame;
a head plate welded to the peripheral frame;
tooth cleaning elements extending outwardly from the head plate and having a length, the tooth cleaning elements being AFT mounted to the head plate; and
a tissue cleanser having a height, the tissue cleanser formed of an elastomeric material and comprising a base in the second surface and a plurality of tissue engaging elements extending outwardly from the base;
wherein a head height comprising the thickness of the head, the length of the tooth cleaning elements, and the height of the tissue cleanser is less than 17.7 mm.

2. The toothbrush of claim 1, wherein the thickness of the head is between approximately 3.6 mm and approximately 6.2 mm.

3. The toothbrush of claim 1, wherein the thickness of the head is approximately 3.6 mm.

4. The toothbrush of claim 1, wherein the tooth cleaning elements have a diameter of less than 7 mil.

5. The toothbrush of claim 1, wherein the height of the tissue cleanser is approximately 0.5 mm.

10 6. The toothbrush of claim 1, wherein the height of the tissue cleanser is between approximately 0.5 mm and approximately 2.5 mm.

7. The toothbrush of claim 1, wherein the tissue engaging elements are nubs.

15 8. The toothbrush of claim 1, wherein the tooth cleaning elements are bristles.

9. The toothbrush of claim 1, wherein the height of the tissue cleanser is approximately 0.5 mm, and the tooth cleaning elements have a diameter of less than 7 mil.

10. A toothbrush comprising:

a handle;
a head at an end of the handle and having a thickness of approximately 3.6 mm, a first surface, an opposed second surface, and a peripheral frame;
a head plate welded to the peripheral frame;
tooth cleaning elements extending outwardly from the head plate and having a diameter of less than 7 mil, the tooth cleaning elements being AFT mounted to the head plate; and
a tissue cleanser comprising a base in the second surface and a plurality of nubs formed of an elastomeric material extending outwardly from the base and having a height of approximately 0.5 mm;
wherein a head height comprising the thickness of the head, the length of the tooth cleaning elements, and the height of the tissue cleanser is less than 17.7 mm.
